UNITED STATES PATENT OFFICE.

GEORGE H. GLASER, OF CLAREMONT, NEW HAMPSHIRE, ASSIGNOR TO SULLIVAN MACHINERY COMPANY, A CORPORATION OF MASSACHUSETTS.

FEED-CONTROLLING DEVICE.

Application filed February 15, 1919. Serial No. 277,347.

To all whom it may concern:

Be it known that I, GEORGE H. GLASER, a citizen of the United States, residing at Claremont, in the county of Sullivan and State of New Hampshire, have invented certain new and useful Improvements in Feed-Controlling Devices, of which the following is a full, clear, and exact specification.

This invention relates to feed controlling devices and more especially, though not exclusively, to means for controlling the action of the pressure fluid feed cylinder and piston of a pressure fluid impact tool, such, for example, as a stoping rock drill.

15 My invention has among its objects to provide an improved feed controlling device. A further object of my invention is to provide an improved feed braking means which may be attached to a complete stoping drill. 20 Another object of my invention is to provide an improved braking and brake controlling means which may be operated from any point desired. These and other objects and advantages of my improvement will, however, hereinafter more fully appear.

While my improved feed controlling means is adapted to devices wherein the feed cylinder moves relatively to the piston or the piston moves relatively to the cylinder, 30 in the accompanying drawings I have shown the same for purposes of illustration applied to a feeding mechanism of the former type.

In these drawings,—

Fig. 1 is a side elevation of a stoping drill provided with my improved retarding means.

Fig. 2 is a longitudinal sectional view of a part thereof taken substantially on the line 2—2, Fig. 1.

40 Fig. 3 is an enlarged detail sectional view taken on the line 3—3, Figs. 1 and 2.

In this illustrative construction I have shown a pneumatic hammer 1 having a piston 2 movable therein and adapted in its forward movement to impart a blow to the shank end of a drill steel 3 to force the bit

make the piston air tight with respect to the cylinder 5. The rear end of the air feed cylinder 5 is partially closed by a bushing 9, the air feed piston passing through an opening formed centrally therein. In stoping drills wherein pressure fluid is admitted to both sides of the air feed piston head, this bushing will constitute the rear cylinder head.

As is common in devices of this type now used commercially, a pneumatic cylinder head plug 10 is carried by the cylinder head block 4, this plug being provided with a collar 11 formed thereon in such a manner that it projects into the air feed cylinder 5 and that a recess 12 is formed between this collar and the forward end of the feed cylinder. A recess 13 is formed in the feed piston 7 in axial alinement with the collar 11 in such a manner that the collar may be received by the recessed piston head when the latter is in its innermost position, and a non-positive locking ring 14 is mounted in this recess 13 to frictionally engage the outer surface of the collar 11 to hold the piston 70 against displacement when it is desired to transport the stoping drill.

In the form of the device shown, a handle 15 is provided by means of which the operator keeps the pneumatic hammer from rotating during the drilling operation and, as is common in devices of this type, this handle is made hollow in order that it may

35 serve as an oil reservoir, a filling cap 16 being provided on the outer end of the handle 15 to permit the filling of the latter

means.

Fig. 2 is a longitudinal sectional view of a part thereof taken substantially on the line 2—2, Fig. 1.

40 Fig. 3 is an enlarged detail sectional view taken on the line 3—3, Figs. 1 and 2.

In this illustrative construction I have shown a pneumatic hammer 1 having a piston 2 movable therein and adapted in its forward movement to impart a blow to the shank end of a drill steel 3 to force the bit

end of the latter against the material to be cut. Mounted adjacent the rear end of the

50 Mounted on the rear end of this cylinder 1 is a cylinder head block 4 which forms the forward cylinder head of an air feed cylinder 5, the latter having mounted therein an air feed piston rod 6 carrying on its inner end an air feed piston 7. The latter is preferably provided in a well-known manner with a plurality of cup leathers 8 to

100 pneumatic feed cylinder is a circular metal ring 20 which may be fastened to the cylinder 5, the latter having mounted therein being provided with ears 21, as is clearly

105 shown. In the form of my improvement herein shown, a sleeve 22 is carried on the same end of the feed cylinder, the sleeve

110 having a sliding fit for a portion of its

length on the cylinder, and being rigidly attached thereto by means of bolts 24 passed through lugs 23 formed on the sleeve and the ears 21 formed on the flange 20. This sleeve is provided with a hole adapted to receive the air feed piston rod 6, as shown.

The retarding element, as shown herein, consists of a disk 25 having a hole formed eccentrically therein, the circular wall of this hole being preferably provided with a brake lining 26 of asbestos fiber or other similar material. The aperture in the disk receives the air feed piston rod 6 and is adapted, when moved out of a plane substantially at right angles to the axis of the piston, to force the friction band 26 against the piston rod and retard the longitudinal movement of the piston 7 in the cylinder 5. This disk is preferably placed within the sleeve 22 and is preferably attached to this sleeve by an ear 27 fastened to the disk 25 near the thinner wall of the disk, ears 28, preferably formed integral with the sleeve, and a pin 28' passed through the ears, as shown. For the purpose of normally retaining the disk in a plane substantially at right angles to the axis of the feed piston rod there is provided a small coiled spring 29 seated in a recess 30 in the end plate 22' of the sleeve and adapted to press against the disk near the thicker wall of the latter to move this edge of the disk away from the end wall of the sleeve. The hole is formed eccentrically in the disk 25 in order to permit the placing of the pivot 28' between the disk and the sleeve 22 and to allow the disk controlling means to act upon the opposite side of the disk.

In my improved feed controlling means, I preferably employ means whereby the disk may be moved out of the aforesaid plane, and whereby this movement is easily performed by the operator no matter what the length of the feed pressure cylinder 5 may be, nor the position in which the stoping drill may be placed when working. In my improved form, this means preferably consists of an actuating rod 31 placed substantially parallel to the cylinder 5, the rod carrying on one end coarse threads 32 co-acting with coarse threads 33 formed on the inner wall of the sleeve 22, whereby when the rod is rotated a small projection 34 formed on the end of the rod within the sleeve forces the disk toward the end plate of the sleeve against the tension of the spring 30, thereby binding the friction band against the feed rod 6. To bring the control of the rod 31 easily within the grasp of the operator, I preferably extend the rod 31 along one side of the cylinder 5 to a point adjacent the head block 4, and support this end by means of a split ring 35 which is clamped securely to the cylinder 5 by a tangential bolt 36. As shown, the rod 31 ex-

tends through an opening in this ring and carries on its end adjacent the head block a U-shaped clip 37 securely attached to the rod 31, a space 38 being provided between this clip and the ring to permit the longitudinal movement of the rod 31 when the latter is rotated. A handle 39 is preferably hingedly secured to this clip by a pin 40 in such a manner that the handle may be rotated about the pin 40 and normally lie out of the way against the ring, as is shown in dotted lines, the operative position of the handle being shown in full lines, in which position the operator may readily and easily rotate the rod 31 to advance the rod by means of the threaded connection with the sleeve 22 to force the disk into binding frictional engagement with the piston feed rod, as has been described.

From the foregoing, the operation of the device will be readily understood, it being clear that the spring 29 normally retains the disk 33 out of frictional engagement with the feed rod, the projection 34 on the end of the control rod 31 serving as a stop to limit the movement of the disk under the pressure exerted by the spring. When the air or other pressure fluid is admitted to the feed cylinder and the pneumatic tool is fed forward toward the work, the pressure with which the feed cylinder forces the tool against the work may be easily regulated by turning the handle 39 so as to obtain any frictional engagement desired between the disk and the rod, and thereby neutralize a part of the pressure exerted by the pressure fluid against the feed piston head 7.

It should be noted that the handle 39 is placed very close to the head block 4 which carries the valve controlling handle 18, so that the handle 39 may be grasped in one hand and the handle 18 in the other, and the operator may easily control all parts of the apparatus without changing his position and without taking his eyes off the work. Further, it should be noted that while this apparatus may easily be built into or as a part of the feed cylinder, it is preferably made as an attachment which may be placed on any feed cylinder now in use without reconstructing the cylinder or the parts attached thereto in any way. It should also be noted that the parts I have employed are easily constructed with a minimum of machine work, that all the elements are simple and strong and will last indefinitely under the most rugged use, and that the only element which will receive any appreciable wear, that is, the friction band, may be easily taken out and replaced without disassembling the feed mechanism at all. The frictional engagement between the threads 32, 33 is great enough to hold the rod 31 in any of its adjusted operative positions and serves as a non-positive locking

means to hold the disk in or out of engaging position. These and other advantages will, however, be apparent to those skilled in the art.

5 While I have in this application specifically described one embodiment which my invention may assume in practice, it is to be understood that the invention is not limited thereto but may be modified and embodied in various other forms without departing from its spirit.

What I claim as new and desire to secure by Letters Patent is:

1. The combination with work performing means and means for feeding said work performing means: of feed controlling means including a non-elastic apertured feed restraining member through the aperture of which a portion of the feeding means extends, and means disposed longitudinally to said feeding means and operable at a distance from the member for moving said member to vary its feed restraining capacity.

25 2. The combination with work performing means and means for feeding said work performing means: of feed controlling means including a non-elastic eccentrically apertured feed restraining member, a friction band between the feeding means and the restraining member, and means for moving said member to vary its feed restraining capacity.

3. The combination with work performing means and means for feeding said work performing means: of feed controlling means including a feed restraining member movable about a pivot not lying in a plane with the axis of the feed controlling means 40 into operative position, means for normally retaining said member in inoperative position, and means for moving said member to vary its feed restraining capacity.

4. The combination with work performing means and means for feeding said work performing means: of feed controlling means including a non-elastic feed restraining member, means for normally retaining said member in inoperative position, and 50 means longitudinally disposed to said feeding means operable at a distance from the member for moving said member to vary its feed restraining capacity.

5. The combination with work performing means and means for feeding said work performing means: of feed controlling means including a non-elastic feed restraining member, means for normally retaining said member in inoperative position, a friction band between the feeding means and the restraining member, and means for imparting a longitudinal component of movement to said member to vary its feed restraining capacity.

65 6. The combination with work perform-

ing means and means for feeding said work performing means: of feed controlling means including a non-elastic feed restraining member, automatic means for normally retaining said member in inoperative position, and manually operable means mounted on the side of and extending longitudinally of the feeding means for moving said member to vary its feed restraining capacity.

7. The combination with work performing means and means for feeding said work performing means: of feed controlling means including a non-elastic feed restraining member, automatic means for normally retaining said member in inoperative position, and manually operable means mounted on the side of and extending longitudinally of the feeding means and operable at a distance from the member for moving said member to vary its feed restraining capacity.

8. The combination with work performing means and means for feeding said work performing means: of feed controlling means including a pivoted non-elastic feed restraining member, automatic means for normally retaining said member in inoperative position, and manually operable means mounted on the side of and extending longitudinally of the feeding means for moving said member to vary its feed restraining capacity.

9. The combination with work performing means and means for feeding said work performing means: of feed controlling means including a non-elastic feed restraining member, automatic means for normally retaining said member in inoperative position, a friction band between the feeding means and the restraining member, and 105 manually operable means mounted on the side of and extending longitudinally of the feeding means for moving said member to vary its feed restraining capacity.

10. In a stoping drill having a pneumatic tool, a feed cylinder attached thereto, a piston having a piston rod and reciprocable therein, a feed restraining device mounted on the opposite end of the feed cylinder from the tool and through which said piston rod extends and is longitudinally movable, and means for changing the angle between said feed restraining device and said piston rod to retard their relative movement.

11. In a stoping drill having a pneumatic tool, a feed cylinder attached thereto, and fluid control means for said tool and feed cylinder: a feed restraining device mounted on the opposite end of the feed cylinder from the tool, and means mounted adjacent 125 said fluid control means for operating said restraining device.

12. The combination with work performing means and means for feeding said work performing means including relatively mov-

able elements, of feed controlling means including a feed restraining member provided with an aperture through which one of said relatively movable elements extends and to which when it is in inoperative position the axis of said last mentioned element is perpendicular, means for normally maintaining said member in inoperative position, and means to move it about a fixed axis to a position in which said first mentioned axis will make an angle therewith.

13. The combination with work performing means and means for feeding said work performing means including relatively mov-

able elements, of feed controlling means including a feed restraining member provided with an aperture through which one of said relatively movable elements extends and which when in a predetermined angular relation to the axis of said last mentioned element is inoperative, means for normally maintaining said member in said inoperative relation, and means for varying the angular relation between said member and said element to effect braking of said feeding means. 15
